JOHN RYER, OF BROOKLYN, NEW YORK.

Letters Patent No. 86,323, dated January 26, 1869.

IMPROVED VAULT-COVER.

The Schedule referred to in these Letters Patent and making part of the same.

To all whom it may concern:

Be it known that I, JOHN RYER, of Brooklyn, in the county of Kings, and State of New York, have invented and made a certain new and useful Improvement in Vault-Covers; and I do hereby declare the following to be a full, clear, and exact description of the said invention, reference being had to the annexed drawing, making part of this specification wherein—

Figure 1 is a plan of the metal frame for the vault-cover;

Figure 2 is a vertical section of the same at the line $x x$, showing the metal ventilating-cover set within said frame; and

Figure 3 is a similar view, with the closed or wooden cap or cover introduced in said frame.

Similar marks of reference denote the same parts.

Vault-covers, heretofore made, have generally been made either of an open or of a closed form, and not capable of change. At some seasons of the year an open vault-cover is required for ventilation, and at other times the cover should be closed, to exclude the weather.

The nature of my said invention consists of a vault-cover, formed with a flanged ring and frame, to set into the stone and receive the movable ventilating-cap, formed of perforated iron, or a movable wooden cap, to close entirely the cover at those seasons of the year when it is desirable to exclude rain, snow, or dampness.

In the drawing—

a is a flanged ring, to set within the stone-work-opening to the vault.

$b b$ are cross-bars, to which the eye c is attached, for receiving the chain that attaches the frame and ring into its place.

d is the hollow movable metal cap, formed to set within the ring a , and having ventilating-openings, $i i$, and knobs, $o o$, to prevent slipping upon the vault-cover.

This cap d may be removed to allow sunlight to penetrate the vault, and the frame $a b$ will be a security against burglars.

The cap-block e , fig. 3, when introduced into the metal frame $a b$, effectually closes the vault-cover against the action of the elements, and a packing of fibrous or other material may be pressed in around the said block e , between that and the rim a , to make the parts water-tight.

The block e , when made of wood, is much better as a surface for walking on in the winter-season, than metal, because it does not become as slippery as metal.

What I claim, and desire to secure by Letters Patent, is—

The vault-cover, formed with the rim a , and cross-bars b , in combination with the removable ventilating-cover d , the flanged ring being also adapted to the closed block e , as and for the purposes set forth.

In witness whereof, I have hereunto set my signature, this 1st day of April, 1868.

JOHN RYER.
